UNITED STATES PATENT OFFICE.

DAVID G. GAY, OF PLEASANT HILL, OREGON.

BUCKLE.

SPECIFICATION forming part of Letters Patent No. 279,148, dated June 12, 1883.

Application filed February 9, 1883. (No model.)

To all whom it may concern:

Be it known that I, DAVID G. GAY, a citizen of the United States, residing at Pleasant Hill, in the county of Lane and State of Oregon, have invented certain new and useful Improvements in Trace-Buckles; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

My invention relates to that class of buckles which are used in the manufacture of harnesses and are known as "trace-buckles," although it may be used on any device in which a buckle of this style is needed.

The object of my invention is to provide a more simple and effective buckle than has heretofore been used; and it consists in an upper and lower frame, which frames are actuated and connected by means of two links or loops, one at each end of the two frames, said frames being provided with an upward and downward projecting pin or lug, respectively; and my invention will be more fully hereinafter described, and shown in the accompanying drawings, similar letters representing similar parts in all the figures, and in which—

Figure 1 is a perspective view of my improved buckle. Fig. 2 is a longitudinal section of the same, and Fig. 3 is a perspective view of the lower frame.

The letter A designates the upper frame, which is connected at its end a' to the lower frame, B, by means of a rectangular link or loop, l. Said link passes through grooves a² a² in upper frame, and grooves b² b² in lower frame, said grooves b² b² in lower frame being long enough to allow said link l to pass loosely through the same, and thus permit the upper frame to be moved backward or forward. The tongue-shaped end a of this upper frame is slightly beveled, so as to allow a link or loop, L, to pass over, and when in position to abut against the shoulders K K, which are formed by the projecting tongue a. At the inside edge of said tongue-shaped projection a, and about midway between both its sides, is a downward-projecting pin or lug, C, which pin passes

through the holes in the trace E, when the upper frame, A, is forced into position by means of the clamping-link L, and thus furnishes a bearing to hold said trace in position. The lower frame, B, is provided at its end b' (which is opposite to end a' of upper frame, A) with elongated grooves b² b², through which the link l is allowed to play, as above described; and about midway between these grooves b² b² is an upward-projecting pin or lug, D, which passes through the holes in the hame-tug F and holds it in position. The opposite end, b, is provided with two grooves, b³ b³, one on each side, through which the clamping-link L works.

Midway between the ends b and b' of the above-described lower frame, B, and projecting from its center piece, b⁴, is a small upward-projecting pin or lug, I, which is designed to rest in one of the holes of the back-strap H, said back-strap resting in the central bent portion, B', of this lower frame, B, and underneath and at right angles to the hame-tug F, in the usual manner.

The whole buckle is held in place by means of a square leather backing or rest, G, which has two leather loops, g g, one at each end, through which loops passes the hame-tug F, which holds the buckle in place between its two loops, g g, by means of its bearing pin or lug D.

The operation of my improved buckle needs no description, as it is obvious that the trace E is to be slipped along over the hame-tug F, underneath the end a' of upper frame, A, until one of its holes is directly below the downward-projecting lug C. Said lug C is then forced into the hole in the trace E by means of the frame A being pressed down into position. The clamping-link L is then pulled over the beveled projecting tongue-shaped end a of the upper frame. To disengage the trace, reverse this operation.

Having thus described my invention, what I claim as new and useful, and desire to secure by Letters Patent, is—

1. The hereinabove-described trace-buckle, consisting of the upper frame, A, lower frame, B, connecting-link l, and clamping-link L, all to rest upon the leather backing G, substantially as and for the purposes set forth and described.
2. The upper frame, A, having in its end a'

two grooves, a^2 a^2 , and having for its opposite end a projecting and slightly-beveled tongue, a , with shoulders K K , and provided with a downward-projecting lug, C , in combination 5 with the lower frame, B , and rectangular links L and l , substantially as and for the purposes herein set forth and described.

3. The lower frame, B , having its projecting ends b and b' provided with grooves b^2 b^2 and 10 b^3 b^3 , and having the projecting lug C , and having in its center a bend or recess, B' , and cen-

tral upward-projecting pin, I , in combination with the upper frame, A , and rectangular links L and l , substantially as and for the purposes herein set forth and described. 15

In testimony whereof I affix my signature in presence of two witnesses.

DAVID G. GAY.
